(57) **CLAIM**

The ornamental design for a discharge device, as shown and described.

DESCRIPTION

FIG. 1 is a perspective view of a discharge device, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a cross-sectional view, taken along line 8-8 of FIG. 6.

The broken lines shown in the drawings depict portions of the discharge device that form no part of the claimed design. The dot-dash broken lines in the drawings define boundaries of the claimed design and form no part thereof.

1 Claim, 8 Drawing Sheets
